ORNAMENT

Clare M. MacKichan, Farmington, and Joseph R. Schemansky, Birmingham, Mich., assignors to General Motors Corporation, Detroit, Mich., a corporation of Delaware

Application January 4, 1957, Serial No. 44,397

Term of patent 7 years

(Cl. D14—18)

We claim:

The ornamental design for an ornament, substantially as shown.
